UNITED STATES PATENT OFFICE.

LEE G. DANIELS, OF ROCKFORD, ILLINOIS.

CAM AND ROLLER CONSTRUCTION.

Application filed April 9, 1921. Serial No. 460,045.

To all whom it may concern:

Be it known that I, LEE G. DANIELS, a citizen of the United States, residing at Rockford, in the county of Winnebago and State of Illinois, have invented certain new and useful Improvements in Cam and Roller Constructions, of which the following is a specification.

This invention relates in general to machine elements, and has more particular reference to cam and roller constructions, especially applicable to metal working machines.

In the design of automatic and semi-automatic metal working machines, it is recognized that cam and roller constructions are very efficient for transmitting feed and other movements such for example as rapid approach, feed and quick return movements; and in other cases it is desired to start with a heavy feed, then change to a fine feed, and then hold the tools at a dwell for finishing before they are retracted. Such construction has, however, been restricted to the smaller sizes and types of machines; and where the more heavy feed pressures are involved, screw and nut elements or other constructions must be employed. This is due to the fact that the ordinary cam and roller construction is inimical to the conditions and requirements of the heavy pressure and heavy duty machines.

The present invention, however, aims primarily to provide a cam and roller construction of such novel design as to make practical and successful its adaptation to metal working machines of all sizes, for the efficient transmission of heavy feed pressures. I have accordingly devised a construction characterized by relatively wide faced, low angle cams and a relatively large diameter roller which follows the cams and is supported at each end by roller bearings in a novel manner and positively held in proper relation to the cams. With a construction of this type, the maximum pressures involved in metal working machines may be most efficiently transmitted under heavy duty service requirements.

Other objects and attendant advantages will be appreciated by those familiar with this art as the invention becomes better understood by reference to the following de-

scription when considered in connection with the accompanying drawings, in which—

Figure 1 is a side elevation of a metal working machine embodying my invention;

Fig. 2, a top view of the cam end of the machine shown in Fig. 1;

Fig. 3, a fragmentary vertical sectional view taken substantially on the line 3—3 of Fig. 2; and

Fig. 4, a detail sectional view taken on the line 4—4 of Fig. 3.

My invention, as mentioned above, is applicable to any metal working machine or the like, in which heavy pressures, such as feed pressures, are to be transmitted. For purpose of illustration, I have taken as an example the application of my invention to an automatic multiple chuck metal working machine of the type in which a multiple of work holders are adapted to be indexed with respect to the tools, and in which the tools are fed toward and from the work holders to simultaneously perform a plurality of cutting operations. In this and other types of metal working machines, a heavy feed pressure is required to effect the cutting operations; and it is to this end that I have devised a novel means whereby these pressures may be most efficiently transmitted.

In the example given, a suitable bed 5 supports upright standards 6 and 7, upon which is mounted for horizontal reception a feed bar 8. The feed bar is connected to a carrier 9 which carries the tool holders (not shown) and is slidable horizontally upon a column 11 concentric with the feed bar 8. A work carrier 12 carries a plurality of circumferentially spaced rotatable work holders or chucks 13 adapted to be successively moved into operative relation with the tools by indexing the work carrier. In this particular machine, the tool carrier 9 equipped with circumferentially spaced tool holders or spindles, not shown, is adapted to be moved by the feed bar toward the work in a rapid approach and a feed movement, and away from the work in a quick return movement.

The present invention has reference to the immediate means for moving the feed bar 8, or in other words, to the means operated by rotary cams for transmitting the desired movements. I prefer to employ cams of a

segmental type adapted to be carried by a suitable cam-carrier such as composed of annular cam plates 14 and 15. As shown in the drawings, these cam plates, formed integral with a hub 16 and suitable reinforcing webs 17, are fixed to a shaft 18 parallel with the feed bar 8. The cam plates are revolved by a worm gear 19 and a worm therefor, on the shaft 21 which 5 may be driven by the shaft 22. In this instance the shaft 18 is employed to drive other mechanism, not shown; and it should be understood that the present invention 10 contemplates any suitable means for revolutionally supporting and for revolving the cam plates. Each cam plate has fixedly secured thereto by bolts 20, one or more segmental cams, designated generally by 23. These 15 cams define an annular cam way 24, in which is disposed a roller 25 carried by the feed bar 8, as will presently be described. It will be observed that the cam plates and 20 cams are of comparatively heavy construction, and that the cams have relatively broad 25 working faces. Referring to Fig. 1 and assuming that the cam plates will be revolved in a clockwise direction viewing the right hand end of the machine, the roller 25 will remain in neutral position until 30 moved to the left by the rapid approach incline 26, and thence in a slow feed movement by the low angle 27 until a point 28 is reached, whereupon the roller and likewise the tool carriage, will be retracted in 35 a quick return movement by the cam incline 29.

The cam roller is supported by and at 40 one side of the feed bar 8, through the agency of the cup and cone type roller bearings, there being one such bearing at each 45 end of the roller. These bearings comprise cone members 31 fixed to the trunnion ends 32 of the roller shaft 33 and annular cup raceways 34 secured to the feed bar. In order to rigidly support the lowermost roller bearing, the feed bar is provided with a 50 yoke reaching inwardly through the cam-way and comprising in the present instance a pair of laterally extending rigid 55 arms 35 embracing the roller and housing the bearing. A retaining plate 36 holds the lower cup bearing in position. Suitable 60 rollers are interposed between the cup and cone race members. These bearings are more efficient for heavy pressures and 65 take care of both the radial and end thrust pressures; but it should be understood that my invention contemplates the use of any suitable bearings or anti-friction 70 bearings for supporting the cam roller in the novel combination claimed herein. The feed bar 8 carries an upstanding arm 37 at the upper end of which is journaled in 75 suitable roller bearings 38, a guide roller 65 39, which is adapted to roll upon and be-

tween the parallel faces 41 of the adjustable gibs 42 carried by the overhead frame structure 43. The rollers 25 and 39 are coaxial and their axis intersects at right angles the axis of rotation of the rotary cam 70 plates. The function of the guide roller 39 or the equivalent guide means, as will be explained more fully hereinafter, is to hold the cam roller 25 in proper operative relation to the cam faces. 75

In operation, the proper line contact will be maintained between the cam roller 25 and the working cam surfaces by means of the guide roller 39, it being apparent that during the feed movement the tremendous 80 thrust on the cam roller tending to force or move the feed bar 8 in a counterclockwise direction viewing Fig. 4, will be effectually resisted by the guide roller 39. The face of the cam roller will thus be held parallel 85 with the working faces of the cams and with the theoretical line contact in a radial plane with respect to the working faces of the cams. Another important factor in maintaining the desired alignment and 90 relation of the cam roller and cams, is the provision of a bearing, preferably an anti-friction bearing of the cup and cone type, at each end of the cam roller, or of suitable means for supporting the roller at 95 each end. This insures a stable and a rigid support for the cam roller.

It is very essential in machines of the character described for heavy and continuous duty and in which a cam and roller are 100 used for bringing the tools and work into and out of operation, that the face of the cam roller shall be kept parallel with the working face of the cam, especially during the heavy pressure of the feed movement. 105 If this parallel relation is not maintained, the working faces of the cam and roller will be only in partial contact, that is, through a part of their width, thereby causing the surfaces to break down and wear 110 unevenly, with the result that accuracy of the machine is seriously impaired. In fact, as a result of such wear, it is impossible to control the feed of the tools with any degree of accuracy. However, the present invention provides a construction whereby 115 heavy and continuous duty may be performed and the highest degree of accuracy in control of the tool is maintained. One of the reasons for this result is that the construction illustrating my invention has none of the disadvantages of other types of cam and roller constructions heretofore employed in automatic machine tools. For example, in those prior constructions employing a rotary cam drum and a roller co-operating with cams on the periphery of the drum for moving the tools and work into 120 and out of operation, the construction is such that the roller is limited to a small 125 130

diameter and the cams to narrow faces. Furthermore, in these prior constructions the rollers usually revolve on a stud which is supported only at one end. Under heavy pressure, the stud will flex more or less, thereby throwing the face of the roller out of parallel with the working face of the cam, and causing only partial contact. Consequently, as the feed pressure increases this would not only cause a breaking down and wearing away of the faces of the cam and roller but also cause inaccuracy in the feed which would be augmented as the feed pressures are increased. If in such construction, the cam and roller faces are increased in width, the greater will be the inaccuracy due to wear; and likewise as the diameter of the roller is increased without increasing the diameter of the stud, the working faces of the roller and cam will be thrown still more out of parallel. If both the stud and roller are increased in diameter, the resistance of the roller revoluble on the stud is correspondingly increased. In the foregoing prior construction, the cam roller is very seldom larger than two inches in diameter and the working faces of the cams more than one inch in width. In other prior constructions, a cam roller is supported on one end of the shaft which is revolvably mounted in one or more bearings at one end, which bearings may be of the anti-friction type, one being located adjacent to the roller and another at the farther end of the roller supporting shaft. Most of the load under heavy pressure will be borne by the bearing next to the roller, causing this bearing to give and the roller shaft to flex, with the result that the face of the roller will be thrown out of parallel with the working face of the cam. The present invention, however, insures that the face of the roller will be kept in full contact with the working face of the cam or cams, making it possible to use a roller of larger diameter and wider face than heretofore; likewise this construction makes it possible to use cams with wide faces and which are of such design as to be capable of substantial mounting. Inasmuch as the pressure that the cams and roller will transmit, assuming that these parts are made of steel of the proper quality and hardness, is directly dependent upon the diameter of the roller and the width of the working faces of the cams and roller, it will be evident that this pressure may be increased proportionally as the diameter of the roller and width of the faces of the cams and roller are increased.

With a construction of the character described, the enormous pressure required for simultaneously feeding a multiple of tools may be very efficiently transmitted in every day service without danger of uneven wear

of the cam and roller faces, nor fracture of these faces due to the heavy pressures, nor of crushing the anti-friction bearings, as has frequently happened in machines heretofore produced. This novel cam and roller construction also permits the use of a most simple and compact mechanism for imparting variable speed movements to either a tool or work carriage or any similar machine element requiring heavy feed pressure. In other words, it may be substituted for the complex gear and clutch trains and other motion reducing and power increasing mechanisms which have heretofore been in common use, especially in the heavy duty type of multiple spindle automatic machines. In such machines, it is necessary to change the cam action in accordance with the particular work or job; and the present invention is especially suited to this end in that the cam plates provide very rigid supports and so constructed and arranged that the segmental cams may be quickly and easily changed. It should be understood, therefore, that my present invention is in no way restricted to use in a machine of the type shown in the drawings, as this particular machine constitutes the subject matter of a separate invention. In other words, the present invention pertaining to the cam and roller construction per se, and to the immediate co-operating parts, is capable of wide application in machine design, and especially as pertains to the transmission of heavy feed pressures.

It is believed that the foregoing conveys a clear understanding of the objects prefaced above, and while I have illustrated but a single working embodiment, it should be understood that the same is capable of considerable modification and change in design and proportions without departing from the spirit and scope of the invention as expressed in the appended claims; in which—

I claim:

1. A cam roller construction of the character described comprising a rotary cam-carrier having axially spaced cam surfaces, a cam roller disposed in the camway between said cam surfaces, a member mounted for reciprocation in a rectilinear path parallel with the axis of rotation of the cam-carrier, and means revolvably supporting said cam roller on said member including a bearing for the cam roller at the inner and outer ends thereof and a supporting member reaching inwardly through said camway supporting the inner bearing, whereby to provide a rigid support for the cam roller and to maintain its face in parallel relation to the faces of the cam surfaces.

2. The combination with a device adapt-

ed to be moved to and fro by a cam and roller, of a pair of oppositely disposed rotary cam plates, segmental cams secured to the inner sides of said plates, and a roller disposed in the cam way defined by said cams and adapted to be moved to and fro thereby.

3. The combination with a device adapted to be moved to and fro by a cam and roller, a pair of oppositely disposed rotary cam plates, segmental cams secured to the inner sides of said plates, a roller disposed in the cam way defined by said cams and adapted to be moved to and fro thereby, and a roller supporting bearing at each end thereof.

4. The combination of a pair of rotary cam plates, changeable segmental cams on the inner sides of said plates, and a roller interposed between the cams and adapted to be moved to and fro thereby.

5. The combination of a pair of rotary cam plates, changeable cams secured to said plates, a roller adapted to be moved to and fro by said cams, and a member moved by the roller.

6. A cam and roller construction of the character described comprising a rotary cam-carrier having axially spaced cam surfaces, a cam roller disposed in the camway between said cam surfaces and having trunnion ends, a member mounted for movement in a rectilinear path parallel with the axis of the cam-carrier, and means revolvably supporting the cam roller on said member including a bearing for each of said trunnion ends and means reaching inwardly through said camway carrying the inner bearing.

7. A cam and roller construction of the character described comprising a rotary cam-carrier having axially spaced cam surfaces, a cam roller disposed in the camway between said surfaces, a member mounted for movement in a rectilinear path parallel with the axis of rotation of the cam-carrier, and means revolvably supporting the cam roller on said member, said means including a supporting structure extending around the roller and through said camway and carrying roller bearings, one inwardly from the inner end of the cam roller and the other outwardly from its outer end, whereby to maintain the face of the cam roller parallel to the faces of the cam surfaces so that the cam pressure will be imparted equally to the face of the cam roller from end to end thereof.

8. In a metal working machine, the combination of a feed bar, a rotary cam, and means operated by the cam for imparting heavy feed pressure to said feed bar comprising a cam roller supported by the feed bar and upon roller bearings at each end of the roller.

9. The combination of a rotary cam, a feed bar adapted to move to and fro in a plane parallel to the axis of rotation of the cam,

a cam roller supported at each end by an anti-friction bearing and disposed wholly at one side of the feed bar.

10. The combination in a mechanism adapted for transmitting heavy feed pressure, a pair of opposite rotary cam plates, segmental cams on the inner sides of said plates, a roller interposed between said cams, a member adapted to be moved by said roller in accordance with the cam action, and means supporting the roller upon said member including a bearing at each end of the cam roller.

11. The combination in a mechanism adapted for transmitting heavy feed pressure, a pair of opposite rotary cam plates, segmental cams on said plates, a roller interposed between said cams, a member adapted to be moved by said roller in accordance with the cam action, a pair of arms fixed to said member and embracing the roller, and a bearing at the outer and inner ends of said arms and upon and between which the cam roller is mounted.

12. The combination of a member adapted to be moved to and fro for transmitting heavy feed pressure, a rotary cam for imparting said pressure, and a relatively wide faced, large diameter roller adapted to be operated by said cam for moving said member, said roller being supported at each end upon said member through the agency of a roller bearing.

13. The combination of a pair of rotary cam plates, segmental cams thereon providing an annular cam way, a roller disposed in said cam way, means adapted to be moved to and fro by said roller, and bearings supporting the cam roller upon said means, one bearing being for the inner end of the cam roller at the inside of the segmental cams, and another bearing being for the outer end of the cam roller at the outer side of the segmental cams.

14. The combination of a rotary cam having opposed surfaces providing an annular cam way, a cam roller disposed in said cam way on an axis at right angles to and intersecting the axis of rotation of the rotary cam, means supporting and adapted to be moved by said roller in accordance with the cam action, and a guide roller carried by said means for holding the face of the cam roller parallel with the working face of the cam surfaces.

15. The combination of a rotary cam, a cam roller disposed on an axis at right angles to and intersecting the axis of rotation of the cam, a feed member carrying said roller and adapted to be moved thereby, and a guide roller carried by said feed member and co-axial with respect to the cam roller for holding the face of the latter parallel with the working face of the cam.

16. The combination of a pair of rotary

cam plates, a segmental cam attached to each cam plate providing a cam way, a cam roller disposed in said way on an axis at right angles to and intersecting the axis of 5 rotation of the cam plates, a feed bar movable in a plane parallel with said axis of rotation, means rotatably supporting said cam roller upon and at one side of said feed bar, whereby the latter will be moved 10 in accordance with the cam action, and a guide roller journaled on the feed bar at the side opposite from said cam roller and substantially co-axial therewith for holding the cam roller in predetermined relation to 15 the rotary cam during operation.

17. The combination of a rotary cam, a feed bar adapted to be moved thereby in a plane parallel with the axis of rotation of the cam, a cam roller in juxtaposition to 20 the feed bar, said bar having rigid laterally extending arms which embrace the roller, a bearing for one end of the cam roller supported by and at the outer end of said arms, and a second roller bearing for the other end 25 of the cam roller supported by the feed bar at the inner end of said arms.

18. A cam and roller construction of the character described comprising a rotary cam having axially spaced cam surfaces, a cam 30 roller disposed in the camway between said surfaces and having a trunnion at each end, and roller supporting means mounted for movement in a rectilinear path parallel with the axis of rotation of said cam-carrier and 35 including a supporting bearing for each trunnion for holding the face of the cam roller parallel with the faces of the cam surfaces at all times.

19. A cam and roller construction of the 40 character described comprising a rotary cam-carrier having axially spaced cam surfaces, a cam roller disposed in the camway between said cam surfaces, a member mounted to travel back and forth in a rectilinear path parallel with the axis of rotation of the cam-carrier, and means revolvably supporting the cam roller on said member and through which the action of the cams is transmitted to said member, including a 45 yoke reaching inwardly through the camway, embracing the cam roller and supporting it at its inner end, whereby to maintain the face of the cam roller parallel with the faces of the cam surfaces under heavy pressures.

20. A cam and roller construction of the 50 character described comprising a rotary cam-carrier having axially spaced cam surfaces, a cam roller disposed in the camway between said cam surfaces, a member mounted to travel back and forth in a rectilinear path parallel with the axis of rotation of the cam-carrier, means revolvably supporting the cam roller on said member and through 55 which the action of the cams is transmitted

to said member, including a yoke reaching inwardly through the camway, embracing the cam roller and supporting it at its inner end, whereby to maintain the face of the cam roller parallel with the faces of the 60 cam surfaces under heavy pressures, and guide means for resisting torsional thrust on said member resulting from the cam action, whereby to maintain the line contact of the cam roller radial with respect to said 65 axis.

21. A cam and roller construction of the character described comprising a rotary cam having axially spaced cam surfaces, a cam roller disposed in the camway between said 70 surfaces, a feed member in juxtaposition to the cam-carrier and mounted to travel back and forth in a rectilinear path parallel with the axis of rotation of the cam-carrier, and means rigidly, revolvably supporting the cam roller on said feed member including an arm rigid with respect to the feed member reaching inwardly through said camway around and beyond the cam roller and providing support for the end of the cam 75 roller nearest to the cam axis.

22. A cam and roller construction of the character described comprising a rotary cam-carrier having axially spaced, changeable cams, a cam roller disposed in the camway between said cams, and means mounted to travel back and forth in a rectilinear path parallel with the axis of rotation of the cam-carrier and revolvably supporting the cam roller by means reaching inwardly 80 through the camway around the roller and providing support for said roller beyond 85 its end nearest to the cam axis.

23. A cam and roller construction of the character described comprising a pair of annular cam-carrying plates in axially spaced, rigid relation, segmental cams removably fixed to the inner sides of said plates, a cam roller disposed in the camway between said cams, a feed bar mounted to travel back and forth in a rectilinear path parallel with the axis of rotation of said cam-carrying plates, means revolvably supporting the cam roller on said feed bar in rigid relation thereto, with the face of the cam roller parallel with the faces of the cams including a yoke rigid on the feed bar reaching inwardly through the camway embracing the roller and providing support therefor beyond its inner and outer ends.

24. A cam and roller construction of the character described comprising a feed bar mounted to travel back and forth in a plane, a cam roller mounted on said feed bar on an axis at right angles to said plane, a rotary cam-carrier on an axis parallel with said plane, having cam surfaces adapted by rotation of the cam-carrier in one direction to act on the cam roller for moving the 125 130

feed bar back and forth in said plane, the cam roller being mounted on the feed bar through the agency of a bearing support at its inner and outer end, and a structure rigid with respect to the feed bar and embracing the roller and providing support for the bearing at its end nearest to the cam

axis, whereby to maintain the face of the roller parallel with the face of the cams, and means for maintaining the line contact between the roller and cams radial with respect to the cam-carrier. ¹⁰

LEE G. DANIELS.
